GEORGE S. HILL, OF STRAFFORD, NEW HAMPSHIRE, ASSIGNOR TO UNITED SHOE MACHINERY COMPANY, OF PATERSON, NEW JERSEY, A CORPORATION OF NEW JERSEY.

BUTTONHOLE-SEWING MACHINE.

1,134,046.

Specification of Letters Patent. Patented Mar. 30, 1915.

Application filed December 20, 1913. Serial No. 307,354.

To all whom it may concern:

Be it known that I, GEORGE S. HILL, a citizen of the United States, residing at Strafford, in the county of Strafford and State of New Hampshire, have invented certain new and useful Improvements in Buttonhole-Sewing Machines; and I do hereby declare the following to be a full, clear, and exact description of the invention, such as will enable others skilled in the art to which it appertains to make and use the same.

The invention relates to buttonhole sewing machines, and more particularly to machines in which the work holding and stitch forming devices are operated to form over-edge stitches extending along the sides and about the ends of the buttonholes.

The object of the invention is to provide sewing mechanism having novel and improved construction and mode of operation which will enable the overedge seam to be formed about the buttonhole at a high rate of speed, and in a uniformly reliable manner.

To this end one feature of the invention contemplates the provision in a machine in which the feed or relative movement between the stitch forming devices and work is continuous during the sewing of a reciprocating work piercing needle which is inclined to its line of reciprocation to compensate for the feed during the advance of the needle through the work. By thus inclining the needle, the lateral deflection of the needle which would otherwise be caused by the relative travel between the needle and work during the advance of the needle is avoided or minimized, so that the feed may be effected at a more rapid rate without materially displacing the needle with relation to the coöperating stitch forming devices.

Further features of the invention relate to improvements in the looper mechanism which operates with the work piercing needle in forming the overedge seam.

The features of the invention will be readily understood from an inspection of the accompanying drawings, and the following detailed description of the mechanism illustrated therein.

In the drawings, Figure 1 is a sectional elevation showing so much of a buttonhole sewing machine as is necessary to illustrate the application of the present invention thereto; Figs. 2 and 3 are detail plan views of the under needle and looper mechanism;

and Figs. 4 and 5 are detail sectional elevations showing the sewing mechanism.

In the drawings the invention is illustrated as embodied in a buttonhole sewing machine having the general construction and mode of operation of the machine shown and described in Patent No. 1,063,880, granted June 3, 1913. This machine is provided with a vertically reciprocating upper needle 2 arranged to piece the work at a predetermined distance from the edge of the buttonhole slit, an oscillating under needle 4 arranged to pass through the buttonhole slit, and a looper 6 which takes a loop of thread from the upper needle and holds it in position for the passage of the under needle therethrough. The work is held during the sewing between clamps 8 and work supporting plates 10 mounted on a clamp carrier 12. The feed or relative movement between the stitch forming mechanism and the work is effected by rotating the stitch forming mechanism and moving the clamp carrier longitudinally and laterally. The stitch forming mechanism is rotated from a gear 14 through connections fully described in the patent above referred to. The clamp carrier is moved longitudinally of the buttonhole by a cam groove in a gear 16 engaging a roll on a stud 18 which is secured in the carrier, and the clamp carrier is moved laterally by a cam groove in the gear 14 engaging one end of a lever 20, the other end of which engages a block 22 playing in a longitudinal slot in the carrier.

The gears 14 and 16 are continuously driven during the sewing, and impart a continuous rotation to the stitch forming mechanism in sewing about the ends of the buttonhole, and a continuous movement of the clamp carrier in sewing along the sides of the buttonhole, so that the feed continues during the periods when the upper needle is in the work as well as during the periods when it is clear of the work. In accordance with the present invention, lateral deflection of the upper needle by the feed as the needle advances into position to coöperate with the looper is avoided or minimized by securing the needle in the needle bar 24 at an inclination to the vertical line of reciprocation of the bar, as indicated in Figs. 4 and 5. These views show the position of the parts when sewing across the end of the buttonhole, at which time the feed is effected by

turning the stitch forming mechanism toward the right. The relative travel of the work with relation to the needle is therefore toward the left in these views, and the needle is inclined forward or in a direction opposite the relative travel of the work. With the needle thus mounted, its inclination to the vertical compensates for the relative travel of the work during the period that the needle is advancing through the work, so that its deflection by the feed is reduced or eliminated. The proper relation between the needle and looper is not therefore materially affected by the feed, even when the feed is effected at a rapid rate. The needle will be deflected during its withdrawal from the work, but the deflection of the needle after the looper has taken the loop does not affect the accurate operation of the parts.

In the construction shown, the looper 6 is adjustably secured in a looper carrying arm 26 which is connected with the end of a horizontally swinging supporting arm 28 by a vertical pivot stud 30. The looper carrying arm is provided with a cylindrical extension 32 arranged to slide through a guide sleeve 34 which cooperates with the swinging arm 28 in determining the path of movement of the looper. The guide sleeve is formed on the upper end of a vertical shaft 36 which is mounted to turn freely in a bearing formed in the turret 38 by which the under needle and looper mechanism is carried. The arm 28 is formed on the upper end of a vertical rock shaft 40, and is operated from the needle operating lever 42 through a link 44 connecting an arm 46 on the lower end of the shaft with an arm 48 on the hub of the lever. As the looper carrying arm 28 is swung from the position indicated in Fig. 3 to the position indicated in Fig. 2, the extension 32 of the looper carrying arm slides through the guide sleeve 34 which turns about its axis and cooperates with the arm 28 in determining the path of movement of the looper. The axes about which the arm 28 and guide 32 swing are so located, and the parts are so proportioned, that the looper is given the proper path to take the loop from the upper needle and carry it over the under needle. This construction enables the looper to be properly timed and move through the proper path with a comparatively short travel of the looper, and also maintains the looper under positive control with comparatively little strain or friction on the parts, so that the looper will operate uniformly and accurately at high speed and with little wear.

While the invention has been shown as embodied in the machine of the patent above referred to, it will be understood that it is not confined in its application to this machine, but may be embodied in other forms of machines. It will also be understood

that the specific construction and arrangement of the parts shown and described is not essential to the broader features of the invention, and may be varied and modified as found desirable or best suited to the construction of the coöperating parts in which the invention may be embodied.

Having explained the nature and object of the invention, and having specifically described one form of machine in which it may be embodied, what is claimed is:—

1. A buttonhole sewing machine, having, in combination, stitch forming devices including a reciprocating needle inclined to its line of reciprocation through the work, and mechanism for relatively moving the work and stitch forming mechanism while the needle is in the work.

2. A buttonhole sewing machine, having, in combination, stitch forming devices including a reciprocating needle inclined to its line of reciprocation through the work, and mechanism for causing a continuous relative movement between the stitch forming devices and work during the sewing.

3. A buttonhole sewing machine, having, in combination, a work clamp, stitch forming devices including a reciprocating needle inclined to its line of reciprocation, and mechanism for causing a continuous relative movement between the clamp and stitch forming devices during the sewing.

4. A buttonhole sewing machine, having, in combination, a work clamp, a reciprocating needle inclined to compensate for the relative travel of the work during the advance of the needle therethrough, devices co-operating with the needle to form overedge stitches, and mechanism for causing a continuous relative movement between the work clamp and stitch forming devices during the sewing.

5. A buttonhole sewing machine, having, in combination, a work clamp, a vertically reciprocating upper needle inclined to compensate for the relative travel of the work during the advance of the needle therethrough, a co-operating under needle and looper, and mechanism for causing a continuous relative movement between the work clamp and stitch forming devices during the sewing.

6. A buttonhole sewing machine, having, in combination, upper and under needles, a looper carrying arm, a pivoted guide having a sliding connection with the arm, and mechanism for reciprocating the arm and swinging it about the pivot of the guide.

7. A buttonhole sewing machine, having, in combination, upper and under needles, a looper carrying arm, and mechanism for actuating the arm including a pivoted guide having sliding connection therewith.

8. A buttonhole sewing machine, having, in combination, upper and under needles, a

looper carrying arm, a swinging arm on which the looper arm is pivoted, and a pivoted guide having sliding engagement with the looper carrying arm.

a vertical pivot, and a guide having sliding engagement with the looper arm mounted 10 to swing about a vertical pivot.

- 5 9. A buttonhole sewing machine, having, in combination, upper and under needles, an arm mounted to swing about a vertical axis, a looper carrying arm connected thereto by

GEORGE S. HILL.
